AMPLIFIER OVERLOAD INDICATOR

Alva R. Hopkins, Merchantville, N. J., assignor to
Radio Corporation of America, a corporation of
Delaware

Application July 15, 1932, Serial No. 622,617

4 Claims. (Cl. 250—20)

My present invention relates to overload indicators, and more particularly to a device for indicating the operation efficiency of a power amplifier of a centralized radio system.

5 One of the main objects of the present invention is to provide a visual indicator for the input circuit of the power amplifier stage of a centralized radio system, which indicator is connected in the amplifier input circuit to indicate 10 full modulation.

Another important object of the present invention is to provide a glow discharge tube indicator for a power amplifier stage of a radio receiver, the function of the glow tube being to 15 inform the user of the receiver when the output stage is overloaded and causing distortion.

Another object of the invention is to provide in combination with the manual volume control device of a radio receiver and a push-pull power 20 amplifier stage, a neon tube overload indicator adapted to be connected in the circuit of the push-pull stage whereby the neon tube is capable of serving as an indicator to inform the operator of the receiver when the manual volume control 25 device should be adjusted for diminishing the input to the push-pull stage to eliminate overloading of the said push-pull stage, it being noted that the average operator is unable to detect the level at which distortion begins, and, this device 30 enables him to operate the amplifier at maximum efficiency and at the same time insure against distortion due to overload.

Still other objects of the present invention are to improve generally the efficiency of power amplifier stages and to particularly provide an overload indicator for a power amplifier stage of a centralized radio system which is not only durable and reliable in operation, but economically 35 manufactured and installed.

40 The novel features which I believe to be characteristic of my invention are set forth in particularity in the appended claims, the invention itself, however, as to both its organization and method of operation will best be understood by 45 reference to the following description taken in connection with the drawing in which I have indicated diagrammatically one circuit arrangement whereby my invention may be carried into effect.

50 Referring now to the accompanying drawing, wherein is shown in diagrammatic manner a conventional single arrangement for a centralized radio system, it will be observed that the channel 55 includes a superheterodyne type of radio receiver divided into two main portions. One of these

main portions comprises the radio receiver proper, and includes the usual grounded antenna circuit A, G connected to a tuned radio frequency amplifier, the latter being connected in well known manner to a first detector, a local oscillator also 5 being connected to the first detector. The first detector is followed by the usual intermediate frequency amplifier, second detector, and a stage of push-pull audio frequency amplification. In a centralized radio system it is customary to 10 provide this main receiver portion as a single unit on a panel of a channel rack.

The second portion of such an assembly usually comprises a power amplifier stage 1 and the conventional power supply circuit 2; the latter 15 usually includes the customary rectifier tubes adapted for connection to an alternating current supply. The power amplifier and power supply circuit are customarily provided as a unit independent of the aforementioned receiver unit, and 20 is mounted on a panel of a channel rack immediately below the receiver panel. This channel rack construction is disclosed in application Serial No. 491,918 filed on October 29, 1930, by Arthur F. Van Dyck. Since this channel rack 25 construction does not comprise the subject matter of the present invention, it is believed sufficient for the purposes of this application to merely refer to the Van Dyck application.

Additionally, it is not believed necessary to 30 go into the details of the superheterodyne receiver portion of the circuit since those skilled in the art are well acquainted with such a radio receiver which covers the entire broadcast band from 550 to 1500 kilocycles. It is merely necessary to point out that the receiver may contain 35 one stage of tuned radio frequency amplification ahead of the first detector, and one stage of 175 kilocycle intermediate frequency amplification, and that the push-pull audio frequency amplifier 40 may include 247 type tubes which are transformer coupled, as at M₁, to the grids of the UX250's of the power amplifier stage 1.

The manually operated volume control, conventionally represented by the arrow 3, is connected 45 between the output of the intermediate frequency amplifier and the grid of the second detector. This is a well known type of volume control device, and it is not believed necessary to show the connection of the variable resistor 50 between the grid of the second detector and the secondary coil of the output transformer of the intermediate frequency amplifier. It is sufficient for the purposes of this application to point out that the numeral 3 designates a manual 55

volume control device which controls the delivery of signal energy to the second detector, and amplified signal energy to the input of the power amplifier stage 1.

- 5 The power amplifier stage 1 comprises a push-pull stage using UX250 type tubes 4, 5. The power supply circuit 2 supplies the filtered rectified alternating current potential to the plates of 4 and 5 through a lead 6, and lead 10 supplies the heating current for the cathodes of tubes 4 and 5 from the power supply circuit in the usual manner. The input transformer M_1 of the power amplifier stage 1 has a mid-tapped secondary, the usual balancing resistors 8 being connected in shunt with each half of the said secondary. The secondary coil of the output transformer M_2 is arranged for connection to the usual monitoring speaker of the channel rack, and also to the distribution channel of the centralized radio system.

As is well known, the secondary of the transformer M_2 may be tapped for four normal output levels, the mid-tap being a common midpoint of all levels and grounded to provide for a balanced-to-ground-distribution system, thus decreasing cross-talk between different channels. The details of the wiring of the different output levels which are connected to the amplifier terminal board for distribution are not shown in order to preserve simplicity of description.

Across the grid circuit of one of the 250 tubes, for example tube 4, is connected the neon overload indicator 10, the indicator tube 10 being mounted on the front of the panel rack, as conventionally designated by the numeral 11, and is visible to the operator of the centralized radio system. The reason for placing the indicator on the output stage is that it is generally good practice to design the equipment so that the output stage is the first to overload. Therefore, this indicates the first distortion. This neon tube, or lamp, is provided in the front panel, and on the same panel which carries the power amplifier unit, to indicate any overload of the power amplifier stage 1. The neon tube may also be said to be connected in the common input circuit of tubes 4 and 5 to indicate full modulation. Of course, as many channel racks as is desired, each including the apparatus shown on the drawing, 50 may be provided in a single installation, and in that case there would be a neon overload indicator on each channel rack.

The neon overload indicator is designed to flash when 90 volts is applied to it, and the grid bias of the tubes 4, 5, is 84 volts. This bias voltage may be obtained in any known manner such as by the connection of a C battery 20 as shown. If the volume control 3 of the receiver is set so that the neon tube is lit, it indicates that the output stage 1 is overloaded and causing distortion, as the tubes are drawing grid current. It is intended that in operation the volume control 3 of the receiver will be set so that the neon tube does not light. Then, as it flashes it serves as an indication that the operator should cut down the volume of the receiver. The neon lamp is lighted intermittently as the audio input to the stage 1 is excessive, the receiver output current being adjusted to a value or level just below the level 70 where the lamp flashes at the peak values of the

audio currents. Where the lamp flashes on the peaks the amplifier is overloaded.

While I have indicated and described one arrangement for carrying my invention into effect, it will be apparent to one skilled in the art that my invention is by no means limited to the particular organization shown and described, but that many modifications may be made without departing from the scope of my invention as set forth in the appended claims.

What I claim is:

1. In combination, with a power amplifier stage including a source of modulated signal energy to be amplified, and a utilization output circuit, means connected to the input circuit of said amplifier and arranged to visually indicate only when the amplifier is drawing grid current due to overloading by the modulating signal energy, said stage including a pair of tubes connected in push-pull, and said means including a gas discharge device connected across the grid circuit of only one of the tubes.

2. In combination with a radio receiver including a tuned radio frequency amplifier, a first audio stage and a power amplifier stage including at least one vacuum tube having a cathode, control grid and audio output circuit, a volume control device located between the tuned radio frequency amplifier and the first audio stage, the grid of the power amplifier stage normally having a large negative bias with respect to its cathode, and a glow discharge tube designed to be inoperative at a voltage equal to the normal bias of said grid, one electrode of said glow tube being directly connected to said grid and the other electrode thereof being directly connected to a point of fixed potential of said power stage grid circuit whereby said discharge tube glows only when the volume control device is adjusted to such a value as to cause grid current to flow 40 in said grid circuit and a resistor connected in shunt across the electrodes of said glow tube.

3. A signaling system including a superheterodyne receiver having a manual volume control device connected between the intermediate frequency amplifier and second detector, a push-pull power amplifier stage connected to the output of said receiver, and a visual overload indicator connected in the input circuit of said push-pull stage, said indicator being designed to be 50 inoperative at a predetermined maximum setting of said volume control.

4. In an amplifying arrangement, the combination of an audio frequency amplifier, means for impressing modulated signal currents across the input terminals of said amplifier, a power amplifier comprising two tubes connected in push-pull, a transformer having its primary connected to the output of said first named amplifier and the opposite ends of its secondary to the grids 60 of said power amplifier stage, the said grids having normally a large negative bias, a balancing resistor connected between each of said grids and the midpoint of said secondary coil and a glow discharge tube having its electrodes connected to the opposite ends of one of said balancing resistors, said discharge tube being designed to have a breakdown voltage in excess of the normal bias voltage of said grids.
